APPARATUS AND METHOD FOR MAKING
CENTRIFUGAL CASTINGS

Hans Breitbart, Duisburg-Beeck, Germany

Application November 25, 1933, Serial No. 699,698
In Germany January 16, 1933

10 Claims. (Cl. 22—65)

This invention relates to a method and apparatus for producing castings more particularly for producing castings whereby the molten material from which the casting is made is forced into the form or die by centrifugal forces.

5 An object of this invention is to provide an apparatus for producing castings whereby the molten substance from which the casting is made is equally distributed over the form or die.

10 An object of this invention is to provide an apparatus for the production of centrifugal castings whereby the molten substance from which the casting is made is vertically poured from a distributor into the interior of the die and where- 15 by the mouthpiece of the distributor is close to the die.

An object of this invention is to provide a method for producing castings by internally charging forms or dies with the molten substance 20 from which the casting is made whereby the speed of applying the molten substance is definitely adjusted and maintained during the charging period.

An object of this invention is to provide a 25 method for the production of centrifugal die-castings whereby the casting may be made in several layers of a plurality of different casting materials.

An object of this invention is to provide a 30 method and apparatus for the production of centrifugal die-castings whereby the molten substance from which the casting is made can be poured into the interior form at various speeds at individual parts of the form according to the 35 quantity of substance required at the individual parts of the form and the thickness of material required at the individual parts of the casting.

An object of this invention is to provide a 40 method and apparatus for the charging of casting forms or dies with the molten material from which the casting is made whereby the molten material is poured in a steady stream of definite dimensions and with equal speed into the form and all splashing or discontinuation or varying 45 of the intensity of the stream is prevented.

An object of this invention is to provide a 50 method and apparatus for producing castings particularly castings of great longitudinal dimension and whereby the molten substance from which the casting is made is equally distributed over the whole length of the casting.

An object of this invention is to provide a 55 method and apparatus for producing castings whereby the molten substance from which the casting is made is brought into a distributor

and therefrom forced into the form by the application of gas under pressure and whereby the speed of the pouring process is much increased and the temperature of the molten substance is low.

Further and other objects of the present invention will be hereinafter set forth in the accompanying specification and claims and shown in the drawings which, by way of illustration, show what I now consider to be a preferred embodiment of the invention.

In the drawings:

Fig. 1 is a cross-section through a diagrammatic showing of the complete casting set up.

Fig. 2 is a cross-sectional view along line A—A 15 of Fig. 1, the distributor being in loading position.

Fig. 3 is a cross-sectional view along line A—A 20 of Fig. 1, the distributor being in charging position.

Fig. 4 is a detail view of part of the distributor.

Fig. 5 is a longitudinal view of a modified distributor.

Fig. 6 is a cross-section through the modified distributor in loading position.

Fig. 7 is a cross-section through the modified distributor in charging position.

Fig. 8 is a longitudinal view of a distributor having different pouring openings.

Figs. 9 and 10 are isometric showings of a modified distributor with an adjustable mouth.

Fig. 11 shows a different modification of the mouth piece of a distributor.

Fig. 12 is a cross-sectional view of a modification of the apparatus having a mouth piece independent from the trough for the molten substances.

Fig. 13 is a cross-sectional view of an apparatus according to my invention showing more particularly the mechanism of the mouth piece.

Fig. 14 is a cross-sectional view of an apparatus according to my invention showing a modification of the mechanism of the mouth piece.

Referring more particularly to the drawings: Figs. 1, 2, 3 and 4 illustrate an apparatus for carrying out a casting operation according to my invention. The tiltable trough 1 is within the hollow form 2 which is in horizontal position. Trough 1 is provided with a flange 3. This, together with the adjustable plate 4 which is arranged above flange 3, forms a mouthpiece which terminates in slot 5. The adjustable plate 4 may be so designed that slot 5 may be entirely closed by the plate. The trough is revolvably supported at both ends by the extensions 6 resting on suit-

able bearings not shown. Fig. 2 shows the trough in a position in which it may be loaded with the molten substance. In Fig. 3 the trough is slightly tilted and the molten substance is discharged through slot 5. However, this is not the normal discharge position. For this purpose the trough is tilted much more and the molten substance is poured out in a vertical stream as indicated on Fig. 7. When making a casting, trough 1 is loaded with the molten substance from which the casting is to be made and the form 2 is rotated. Then the trough is tilted until the molten substance pours out in a vertical ribbon-like stream which gradually builds up the casting on the inner side of the form.

Figs. 5, 6 and 7 illustrate a distributor consisting of two equal halves 8 and 9 provided with flanges 10 and 11. The interior and, particularly, flange 11 may be lined with asbestos 12. The two halves are held together by screws or similar means which connect the flanges 11. By choosing a suitable thickness of the asbestos layer 12 between the flanges 11, a corresponding slot 5 will remain open between the flanges 10. A distributor of the type disclosed in Figs. 5, 6 and 7 can be used for forcing the molten substance out of slot 5 by gas pressure. Compressed gas, for example CO₂, may be supplied to chamber 13 after the trough has been filled with molten substance and tilted into the discharge position as shown in Fig. 7.

Fig. 8 shows a distributor designed along the same principles as is the one illustrated by Figs. 5, 6 and 7 but having a slot of different widths: 5, 5' and 5''. Such a distributor is useful when the shape of the casting to be produced varies in size over its length. The part on the left may require most material and is therefore supplied through the wide part 5'' of the slot. The part on the right may require the smallest amount of molten material and is supplied through the narrow part 5 of the slot. If, for example, a cylindrical casting of a certain outside diameter is made by using a type of distributor as shown in Fig. 8, this will have varying wall thickness and varying internal diameter, the smallest diameter being at the left side which is supplied by the wide slot 5'', and the largest internal diameter at the right side which is supplied by the small slot 5. The interior of the distributor may be lined with firebrick 14 and it may also be provided with heating means for protecting the distributor and maintaining a desired temperature within it.

Figs. 9 and 10 illustrate a heavier type of distributor consisting of three parts: the side walls 8 and 9 and a cover 15. The side walls 8 and 9 can be rotated around bolts—not shown—accommodated within the eyes 16; in this way the size of the opening or slot 5 can be changed.

Fig. 11 illustrates a mouthpiece which, instead of having a slot, has a plurality of openings of different configuration to provide for the correct amount of molten material and for the most desirable configuration of the stream of molten material in accordance with the requirements of the casting to be produced.

Fig. 12 illustrates a design of my apparatus which is particularly adapted to produce large and/or long castings. Distributor 18 with mouthpiece 20 is separate from trough 17. Auxiliary trough 17 may be large compared with distributor 18. This increases the stability and strength of the apparatus inasmuch as the small distributor 18 must not hold much material and the large,

practically stationary trough 17 can be built very strong. Trough 17 may be refilled during the centrifugal casting operation. It may be refilled several times and, if desired, with different materials, while the main distributor 18 remains within the form and the casting operation goes on without interruption. The large trough 17 having a revolvable cover plate 22 and a mouth 21 may remain stationary during the casting period and is tilted around the bolts 19 only at the end of the period in order to be completely emptied. The position of the trough shown in Fig. 12 is that at the end of the casting operation, i. e. when the trough is completely emptied. It is obvious that the trough may also be completely closed and gas pressure applied to force the molten material out of the auxiliary trough 17 at higher velocity into the main distributor 18 and therefrom into form 2.

Fig. 13 illustrates a mechanism for adjusting the width of the pouring slot 25. This slot is formed by the flat parts 26 and 27 of the hollow cylinders 23 and 24. Both cylinders are revolvably mounted on trough 1. Each cylinder is provided with a spur gear 30 and 31 which are operatively connected by the intermediary gear 32. This mechanism effects a turning of both cylinders in the same direction upon revolving one cylinder or the intermediary gear 32. The width of the slot is thereby changed from the widest opening position, i. e. when the flat parts 26 and 27 of both cylinders are parallel to one another, to the smallest opening or completely closed position, i. e. when the flat parts are at an angle and the cylinder surfaces touch each other.

Fig. 14 illustrates a mouth mechanism whereby the speed of the outflowing molten material can be increased or decreased and also the direction of the stream of the molten material can be changed. The slot is formed by two revolvable cylinders 28 and 29 which are revolved in opposite directions. This can be effected by providing gears on each cylinder which are in mesh with one another or by revolving only one cylinder and transmitting the movement to the other cylinder by using the friction between the cylinders and the outflowing molten material. The mechanism can also be so constructed that only one of the cylinders revolves. It is apparent that, when the cylinders revolve in the direction as indicated by arrows 33 and 34, the speed of the outflowing material is increased, while, when they revolve in the opposite direction, this speed is decreased. When the cylinders are operated at different speeds, the direction of the outflowing stream is changed.

The interior of the hollow cylinders 23 and 24 on Fig. 13 and 28 and 29 on Fig. 14 may be cooled, for example by circulating molten lead therethrough.

The arrangements shown in Figs. 13 and 14 may also be incorporated in such construction of trough 1 which permits the application of gas pressure for forcing the molten material out of the trough at increased and adjustable speed.

The casting operation may be carried out in different ways. The total amount of molten material required may be poured into the form while the latter stands still. The molten material discharged from a distributor according to my invention, particularly if the mouthpiece is close to the interior of the form, is absolutely quiet, i. e., there are no waves or other movements and the centrifugal casting process, i. e., the rotation of the form can be started immediately after

the form has been charged. One may also at first pour only part of the molten material required into the form at a standstill and add the rest while the form is being rotated; in this way the wall of the casting is built up gradually. A third modification of the method is to pour the molten material into the rotating form and gradually build up the walls of the casting from the start. Several layers of different substances may be cast on top of each other by this method; for example a heavy layer of soft steel may thus be bedded in between two thin layers of special steel, nickel, etc. Hollow blocks built up in this manner may afterwards be rolled into rails, profile bars, sheets and the like.

While I believe the above described embodiments of my invention are preferred embodiments, I wish it to be understood that I do not desire to be limited to the exact details of process, design and construction shown and described, for obvious modifications will occur to a person skilled in the art.

What I claim is:

1. In an apparatus for making centrifugal castings from a molten material, a form, means for rotating said form, a tiltable distributor for said molten material within said form, said distributor having an adjustable opening for pouring out said molten material and means for adjusting the size of said opening.

2. In an apparatus for making centrifugal castings from a molten material, a revolvable form, a tiltable trough for receiving said molten material and a distributor adapted to receive said molten material from said trough and to pour said molten material into said form, both said trough and said distributor being located within said form.

3. In an apparatus for making centrifugal castings from a molten material, a revolvable form, a tiltable distributor for said molten material and located within said form, said distributor having a mouthpiece consisting of two cylindrical bodies, each of said bodies having a flat part, said flat parts being located substantially opposite one another, and means for rotating said cylinders in like direction thereby varying the angularity of said flat parts with respect to each other and thereby varying the width of the opening of said mouthpiece.

4. In an apparatus for making centrifugal castings from a molten material, a revolvable form, a tiltable distributor for said molten material located within said form, said distributor having a slot-like mouthpiece for discharging said molten material into said form, and means for adjusting the velocity of the molten material discharged through said mouthpiece, said means consisting substantially of two cylindrical bodies adapted to revolve in a direction opposite to one another, and provisions for adjusting the revolving speed of said bodies.

5. In an apparatus for making centrifugal castings from a molten material, a revolvable form, a tiltable distributor for said molten material and

located within said form, said distributor having a slot-like mouthpiece for discharging said molten material into said form and means for adjusting the velocity of the molten material discharged through said mouthpiece, said means consisting substantially of two cylindrical bodies adapted to revolve in a direction opposite to one another and provisions for individually adjusting the revolving speed of said bodies.

6. In an apparatus for making centrifugal castings from a molten material, a revolvable form, a tiltable distributor for said molten material and located within said form, said distributor having a slot-shaped mouthpiece for discharging said molten material into said form, and means movably associated with said mouthpiece for adjusting the velocity of the molten material discharged through said mouthpiece.

7. In an apparatus for making centrifugal castings from a molten material, a revolvable form, a trough for receiving the molten material and having an adjustable mouthpiece and a distributor adapted to receive the molten material from said trough and to pour the molten material into said form, both said trough and said distributor being displaced within said form.

8. Method of making centrifugal castings consisting in filling a container completely located within the casting form and having an adjustable mouthpiece with the molten material of which the casting is to be made, in discharging the material from said container into a distributor also completely located within the casting form and from said distributor into the interior of the casting form and in adjusting the velocity of the discharging process by adjusting the mouth of said container.

9. Method of uninterruptedly making centrifugal castings consisting in filling a container completely located within the casting form with the molten material of which the casting is to be made, in discharging the material from said container into a distributor also completely located within the casting form and from said distributor into the interior of the casting form and in refilling said container while the material of the first charge of said container is still being discharged from said distributor into the form.

10. Method of making centrifugal castings consisting of several layers of different materials consisting in filling a container completely displaced within the casting form with the molten material of which the outermost parts of the casting are to be made, in discharging the material from said container into a distributor also completely located within the casting form and from said distributor into the interior of the casting form, in refilling said container with another molten material of which more interior parts of the casting are to be made and in discharging the other material from said container into said distributor and therefrom into the interior of the casting form and in repeating the afore stated process as often as different layers are desired.

HANS BREITBART. 65
